EXTENSION BRACKET FOR HIGHWAY
GUARD CABLESElmer K. Cole, Winterset, Iowa, assignor to Wej-
Lock Manufacturing Company, Winterset,
Iowa, a corporation of Iowa

Application September 6, 1932, Serial No. 631,793

1 Claim. (Cl. 248—31)

In the construction of highway guard fences it is now generally recognized that there are numerous advantages in having extension brackets for holding the cables spaced from the posts. 5 Their use, however, is limited due to their expense and the high percentage of breakage, both to the brackets and to automobiles, under working conditions.

The object of my invention is to provide a bracket of this character of simple, durable and inexpensive construction, which may be constructed of sheet metal without waste of material, and which may be cut and formed with simple and inexpensive material, and which is 10 strongly braced and supported against all the strains and shocks to which it is subjected in use.

A further object is to provide an improved cable and extension bracket supporting device 20 of simple, durable and inexpensive construction which may be readily, quickly and easily applied, and which when in position will firmly and securely support the extension bracket on the post and the cable in the cable supporting device.

25 My invention consists in the construction, arrangement and combination of the various parts of the device, whereby the objects contemplated are attained, as hereinafter more fully set forth, pointed out in my claim, and illustrated in the 30 accompanying drawing, in which:

Figure 1 shows a top view of my improved bracket applied to a post, shown in section, and having a cable in position in the hook of the bolt.

35 Figure 2 shows a side view of same with a portion of the bracket broken away to show the locking construction.

Figure 3 shows a perspective view of the bracket.

40 Figure 4 shows a detail vertical sectional view through a portion of the extension bracket and a modified form of cable extension hook therein; and

Figure 5 shows a plan view of the cable supporting device in its normal position open to receive a cable.

45 Referring to the accompanying drawing it will be seen that the bracket proper is formed of two pieces of sheet or plate metal, one forming the base and the other the bracket body. The base 10 is a rectangular piece of metal curved to conform to a round post and having two outwardly extended lugs 11 formed by cutting and pressing outwardly.

50 The body of the bracket is also formed com-

plete of a single piece of sheet metal of rectangular shape and hence without waste. It comprises two sides 12 having inwardly extended flanges 13 and an outer end member 14, which also has inwardly extended flanges 15, and a bolt opening. This extension bracket body portion may obviously be made of a single piece of sheet or plate metal with simple cutters and formers, and without waste. The flanges 13 and 15 support and brace the sides 12 so that relatively 5 light metal may be used.

The assembly of the base and body is done by simply bending the flanges 13 at their inner corners under the base 10 and at 16, which firmly secures the parts together against separating and 10 up and down movements while the lugs 11 brace the body sides against spreading movement.

My improved cable and bracket supporting device is formed complete of a single piece of half round metal bar. The two end portions thereof 20 are straight as indicated at 17 and are arranged substantially V-shaped with relation to each other, and at the center or apex of the V I have formed a substantially circular loop 18. One end of the bar is preferably longer than the other and 25 both ends preferably have their outer end portions beveled at 19 for easy insertion through a hole in a post.

I have also provided a fulcrum device 20 consisting of a circular fulcrum plate flat on one 30 side and having a central opening through which the cable supporting device may pass, and the opposite side of the fulcrum device is tapered from its center outwardly and toward the flat side of the fulcrum device, as clearly shown in 35 Figure 1.

In assembling my improved extension bracket and cable support I first place the extension bracket against the side of the post adjacent to the highway, and then cause the V-shaped cable 40 supporting device to straddle the cable until the cable rests in the loop 18 as shown in Figure 2. I then press the end portions 17 of the cable supporting device into parallel engaging positions, and then insert these ends through the 45 slot 21 in the outer end of the extension bracket and through the hole in the post. I then place the fulcrum plate on the end portions of the cable supporting device which project beyond the opposite face of the post. The longer one of 50 the ends 17 is preferably below the shorter end. I then with a hammer or the like strike upon this longer projecting end and drive it downwardly until it lies close against or penetrates slightly into the side of the post as shown in Figure 2. 55

Then the remaining end is driven upwardly and into the post in the same manner.

During this bending movement, the end that projects beyond the fulcrum plate will act as a lever, having its fulcrum at the fulcrum plate and this movement will obviously exert a great degree of pressure in a direction tending to draw the looped end of the cable supporting device into the slot 21 in the extension bracket, and also to force and firmly set the extension bracket against the adjacent side of the post.

In this connection it should be explained that I preferably make the loop 18 somewhat larger than the diameter of the cable so that when these parts are assembled, as before explained, and firmly drawn into position, the cable may then move longitudinally within the loop 18. One of the important advantages of this construction is that cable attaching devices of the same size may be supplied for posts of various diameters, and when assembled, as shown in Figure 2, the ends of the cable supporting device do not project beyond the rear of the post. Hence, a relatively long cable supporting device may be used on a post of relatively small diameter without leaving any objectionable projection beyond the post.

By using a cable supporting device formed of a half round metal bar, I gain a substantial advantage in that the part of the loop shaped member that projects beyond the cable projects only half as far toward the highway as would a hook round in cross section, so that an automobile striking the cable will slide along it past the post and will not be caught by the hook and the bracket and thus escape injury.

With my improved apparatus, I have demonstrated by actual tests that with a half round rod $\frac{3}{8}$ " in diameter at its widest point, assembled in the manner and by the method shown, and by applying strains to the cable either upwardly and downwardly or outwardly toward the highway away from the post, approximately five times the amount of strains may be thus applied without injury or damage to the device as compared with an ordinary $\frac{3}{8}$ " bolt with a hook shaped end to receive the cable of the kind now in common use.

In the modified form shown in Figure 4, I have shown an ordinary bolt 21, having a hook shaped end 22 to receive the cable, and this hook shaped end is flattened at 23 and this performs the useful functions of, first reducing to a minimum the amount to which the hook projects beyond the cable, so that an automobile which strikes the cable and slides along it past a post will not be caught by the hook and the bracket

will escape injury; and second this flattening of the hook widens it at the point where it enters the openings in the end 14, thereby limiting the inward movement of the hook.

This prevents the hook from tightly gripping the cable so that if a cable receives a heavy impact, the adjacent portion of the cable passing through several posts may yield enough to prevent breakage of the cable or dislodging of the posts.

In the outer surface of the short end of the hook I have formed a notch 24 directly in line with the adjacent portion of the outer end 14. The function of this notch is as follows:

Assuming that a heavy strain is applied to the cable in a direction outwardly from the post or toward the short end of the hook, sufficiently to bend the hook, then the notch will receive the adjacent edge of the outer end portion 14 and lock the hook against further movement, thus providing an automatic lock against such movements of the free end of the hook. This advantageous feature is provided with a minimum of expense and does not in any way interfere with the easy assembly of the parts.

In practical use the base member is set adjacent the side of a post and a certain radius of the base will fit posts of considerably larger or smaller diameter, as hereinafter explained. Then the bolt is inserted through the bracket and into the post. Then the cable is placed in the hook and finally the nut is applied to the bolt and screwed up tight.

The inward movement of the bolt relative to the bracket is stopped by the enlarged outer end of the hook so that pressure applied by the tightening of the nut forces the side 12 against the end portions of the base into tight fitting engagement with the post and prevents injury to the post if heavy blows are applied to the bracket or cable. If the radius of the base is less than that of the post, it will expand to fit the post when the nut is tightened.

I claim as my invention:

An extension bracket for highway fence cables comprising a base shaped to substantially conform to the side of a post, and having outwardly extended lugs, a body portion comprising two sides and an outer end portion with the sides engaging the base and the lugs, portions of the sides being bent under the base for securing the parts together, a cable supporting device passed through the said outer end portion, and a cable receiving loop formed therein.
